UNITED STATES PATENT OFFICE.

WILLIAM II. JAMOUNEAU, OF NEWARK, NEW JERSEY.

DESIGN FOR A SPOON, &c.

SPECIFICATION forming part of Design No. 20,871, dated June 30, 1891.

Application filed May 9, 1891. Serial No. 392,245. Term of patent 7 years.

To all whom it may concern:

Be it known that I, WILLIAM II. JAMOUNEAU, a citizen of the United States, residing at Newark, in the county of Essex and State of New Jersey, have invented and produced a new and original Design for Handles for Spoons, Forks, or other Articles, technically known to the trade as "Flat ware;" and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The figure of the drawing is a front plan of a spoon of my new design, of which the following is a specification, the one figure being deemed sufficient to fully illustrate the same.

The leading feature of the design consists in the handle of a spoon or fork which is in a shape indicative of a man's head and bust and mining implements.

In said drawing, *a* indicates a bowl of a spoon, the concave side being shown, and *b* indicates the handle of said spoon. At the

end of the handle opposite the bowl the same is broadened out and has a shape of a man's head *c* and bust *d* in outline and front ornamentation. Below the bust portion the handle is ornamented with representations of mining implements, a pick *f* and shovel *g* being particularly displayed. From the blade of the shovel coin-like disks *h* are represented as falling. Toward the bowl the narrow shank *h'* of the handle is ornamented with a representation of mountain *i*.

What I claim is—

The design for a spoon or other article of flat ware herein described, which consists of a handle the front of which is ornamented with representations of the head of a man and mining implements, substantially as shown and described.

In testimony that I claim the foregoing I have hereunto set my hand this 7th day of May, 1891.

WILLIAM II. JAMOUNEAU.

Witnesses:

CHARLES H. PELL,
OSCAR A. MICHEL.
